THEIR ATTORNEY

UNITED STATES PATENT OFFICE.

CLAUDE J. FOWLER, OF YONKERS, AND JEFFERSON FOWLER, OF RED CREEK, NEW YORK.

AUTOMATIC DAMPER.

Application filed May 8, 1923. Serial No. 637,571.

To all whom it may concern:

Be it known that we, CLAUDE J. FOWLER and JEFFERSON FOWLER, residing at Yonkers, New York, and Red Creek, New York, respectively, have invented certain new and useful Improvements in Automatic Dampers, of which the following is a full, clear, and exact description.

The invention relates to improvements in automatic dampers for stove pipes, chimneys, smoke stacks, and the like.

The object of the present invention is to improve the construction of automatic dampers, and to provide a simple, efficient and inexpensive damper capable of automatically closing when the draft through the stove pipe is increased by the heat and products of combustion from a fire, whereby the fire is controlled and a saving of fuel effected.

A further object of the invention is to provide an exceedingly sensitive automatic damper equipped with a pair of weights to partially counter-balance the damper to render the same sensitive, one of the weights being adjustable whereby the damper may be set in any desired position.

Another object of the invention is to provide a damper which is exceedingly sensitive and at the same time is provided with means to damp out undesirable vibrations or swinging movements of the damper such as frequently accompany sensitiveness in a device of this kind.

With these and other objects in view, the invention consists in the construction and novel combination of parts hereinafter fully described, illustrated in the accompanying drawing, and pointed out in the claims here-to appended.

40. In the drawing:

Fig. 1 is a side elevation of an automatic damper, constructed in accordance with this invention and shown applied to the stove pipe;

Fig. 2 is a longitudinal sectional view of the stove pipe showing the damper in position therein, certain of the external parts of the damper being broken away;

Figs. 3 and 4 are enlarged detail views of 50 a portion of the invention;

Fig. 5 is a section on the line 5—5 of Fig. 2; and

Fig. 6 is a fragmentary view similar to Fig. 1 showing one operative position of the 55 damper.

In the accompanying drawing, 10 designates an egg-shaped damper plate constructed of sheet metal and mounted within a vertical stove pipe 11 on a horizontal spindle 12, extending across the damper plate 10 above the middle thereof, the depending portion of the plate or that portion below the spindle 12 being longer and heavier than the upper portion thereof. The damper plate is adapted to swing from its open position 10 illustrated in Fig. 1 to its closed position 10^a as illustrated in Fig. 6 in which position, it will be noted, the lower portion of the plate is spaced from and does not touch the adjacent inner face of the stove pipe and the upper portion is spaced a still greater distance from the stove pipe. The plate 10 thus does not come in contact with the pipe. This construction avoids the annoyance incident to the plate 10 striking the pipe and also prevents the accumulation of soot between the pipe and the damper plate. The means for limiting the movement of the damper plate will be hereinafter described.

The main spindle 12 consists of a wire 80 having straight side portions 13 and an intermediate upwardly bent portion 14. The side portions 13 are adapted to be hooked under the downwardly opening hooks 15 formed at the lateral edges of the plate 10. 85 The portion 14 is engaged on the tongue 16 which is formed out of the damper plate 10 and provided with an upwardly opening hooked portion 17 as shown in Figs. 2 and 5. The hook 17 is shallow so that the bent portion 14 may be readily disengaged therefrom. The damper plate may be readily attached to spindle 12 by merely engaging the side portions 13 of the spindle under the hooks 15 and then springing the bent portion 14 over the hook portion 17. This provides a simple means for securing the plate to the spindle and for readily attaching or detaching it.

Main spindle 12 is pivoted in the walls of pipe 11 and one end thereof is bent radially to provide a short arm 18 and is then bent back on itself in a direction substantially parallel to the short arm 18 to provide the main arm 19. Arms 18 and 19 lie in the same vertical plane, and form a loop between them designated by reference character 20.

Passing through pipe 11 just below main spindle 12 is an auxiliary spindle 21 having a bent auxiliary arm 22 terminating in an 110

upwardly directed hook 23 which passes through the loop 20 as best illustrated in Figs. 1 and 4. One function of spindle 21 is to stop the damper plate 10 from movement past the vertical or open position shown at 10. Spindle 21 is preferably located a slight distance forward (to the left) of the main spindle 12 so that the plate will be held slightly inclined and in such a position that there will always be a pressure on the lower side of the plate, due to the up draft, tending to move the plate towards its closed position.

Carried on the hook 23 and adjacent to the arms 18 and 19 is a washer 24 and adjacent thereto is ring 25 from which is suspended an auxiliary weight 26. Hook 23 of the auxiliary arm bears downwardly on the main arm 19 of loop 20 and tends to rotate the damper towards its open position. The weight 26 offsets to some extent the main weight 27 which tends to move the damper to its closed position. As clearly shown, weight 27 is carried on that portion of main arm 19 which is to the right of the vertical plane passing through spindle 12 and is movable along the arm 19 by means of a spiral 28 formed of wire and encircling the arm, which spiral is turnable by means of knob 29 to advance the weight along the arm in either direction. By means of this spiral adjustment a considerable turning movement of the knob 29 may be translated into a relatively small movement of the weight 27 along the arm 19 thus making possible quick and accurate adjustments of the damper.

The relation of the arms and weights relatively to the spindles is such that the weights enjoy substantially rising and falling movements during motion of the damper, as distinguished from lateral swinging or pendulum movements, which latter are objectionable for the reason that they are likely to synchronize with the natural swinging movements of the damper and thereby cause violent swaying thereof and therefor uncertain regulation as well as objectionable noise.

Additional means for damping out unnecessary vibration or swinging movement of the damper is to be found in the particular arrangement of the loop 20, the washer 24 and the weight 26. Upon reference to Fig. 4 it will be seen that hook 23 is so curved that the washer 24 pressed by the ring 25 is urged into frictional contact with the arms 18 and 19 carried by the main spindle. Enough friction is thus introduced into the apparatus to damp out undesirable swinging movements of the damper without sacrificing sensitiveness of the damper as a whole to variations in draft. It will be understood that the washer 24 may be omitted or the parts modified in shape so as to reduce or increase the friction as desired.

As previously stated, the depending por-

tion of the damper plate 10 does not come in contact with the adjacent inner surface of the pipe 11 when the damper is in its closed position. Motion of the damper towards its closed position is limited by the auxiliary arm 22 which is so shaped that it will strike the main spindle 12 at the point 30, as shown in Fig. 6. A finger 31 is rigidly but adjustably secured on the spindle 12 and may be set to make contact with auxiliary spindle 21 to limit the closing movement of the damper before the arm 22 contacts with main spindle 12 at 30 as above described.

While the form of mechanism herein shown and described constitutes a preferred embodiment of one form of invention, it is to be understood that other forms might be adopted and various changes and alterations made in the shape, size, and proportion of the elements therein without departing from the spirit and scope of the invention.

What is claimed is as follows:

1. In a damper, in combination, a damper plate, a spindle therefor including an arm extending therefrom, a balance weight carried by said arm, and weight means in frictional sliding relationship with the spindle for damping swinging movements of the damper during normal swinging movements thereof. 90
2. In a damper, in combination, a damper plate, a spindle therefor including an arm extending therefrom, a balance weight carried by said arm, and friction means cooperating with the spindle at a point remote from its axis for damping swinging movements of the damper. 100
3. In a damper, in combination, a damper plate, a spindle therefor including an arm extending therefrom, a balance weight carried by said arm, and means pivoted for rotation about a fixed axis and cooperating with the spindle for damping swinging movements of the damper. 105
4. In a damper, in combination, a damper plate, a spindle therefor, weight means for balancing the damper plate, and means for damping swinging movements of the damper, said means comprising a member extending outwardly from the spindle and adapted to turn therewith, and means frictionally resisting movement of the member. 110
5. In a damper, in combination, a damper plate, a spindle therefor, weight means for balancing the damper plate, and means for damping swinging movements of the damper, said means comprising a member extending outwardly from the spindle and adapted to turn therewith, and weight means for resisting movement of the member. 115
6. In a damper, in combination, a damper plate, a spindle therefor, weight means for balancing the damper plate, and means for damping swinging movements of the damper, said means comprising a member extending outwardly from the spindle and adapted to turn therewith, and weight means for resisting movement of the member. 120
7. In a damper, in combination, a damper plate, a spindle therefor, weight means for balancing the damper plate, and means for damping swinging movements of the damper, said means comprising a member extending outwardly from the spindle and adapted to turn therewith, and weight means for resisting movement of the member. 125

damper, said means comprising a member extending outwardly from the spindle and adapted to turn therewith, and means pivoted for rotation about a fixed axis and cooperating with the outwardly extending member for resisting movements thereof.

7. In a damper, in combination, a damper plate, a main spindle therefor, an arm secured to the spindle and extending transverse to a vertical plane passing through the spindle, and spaced weights bearing on said arm to balance the damper, one of the weights being arranged to damp swinging movements of the damper plate.

10 8. In a damper, in combination, a damper plate, a main spindle therefor, an arm secured to the spindle and extending transverse to a vertical plane passing through the spindle, and spaced weights bearing on

20 said arm to balance the damper, one of the weights having slideable frictional engagement with said arm during the movement of the damper plate to effect damping of the movements of the latter.

25 9. In a damper, in combination, a damper plate, a main spindle therefor, an arm secured to the spindle and extending transverse to a vertical plane passing through the spindle, a balance weight bearing on

30 said arm, an auxiliary weight, an auxiliary arm supporting the auxiliary weight, said arm being guided for movement independently of said first-mentioned arm and bearing on the latter.

35 10. In a damper, in combination, a damper plate, a main spindle therefor, an arm secured to the spindle and extending transverse to a vertical plane passing through the spindle, a balance weight bearing on said arm, an auxiliary spindle having an arm connected therewith, an auxiliary weight on the auxiliary arm, said aux-

iliary spindle being near said main spindle and adapted to stop the valve plate in wide open position.

45

11. In a damper, in combination, a main spindle, a damper plate mounted thereon and adapted to turn therewith, a main arm on the spindle, an auxiliary arm, and a weight carried thereby, said auxiliary 50 arm being guided for movement independently of said main arm and having a bearing on the main arm.

12. In a damper, in combination, a main spindle, a damper plate mounted thereon 55 and adapted to turn therewith, a main arm on the spindle, an auxiliary arm pivoted adjacent the main spindle, and a weight carried thereby, said auxiliary arm having a sliding bearing connection with said main 60 arm.

13. In a damper, in combination, a spindle, a damper plate mounted thereon and adapted to turn therewith, means in the path of the valve plate to stop its movement 65 in one direction, and means on the spindle and cooperating with said first-mentioned means for stopping its movement in the opposite direction.

14. In a damper, in combination, a 70 damper plate, a spindle therefor including an arm extending therefrom, a balance weight carried by the arm, and friction means associated with the spindle for damping the swinging movements of the damper 75 during normal operation thereof.

In testimony whereof we hereto affix our signatures.
